UNITED STATES PATENT OFFICE.

MIFFLIN W. BAILY, OF POTTSTOWN, PENNSYLVANIA.

IMPROVEMENT IN ANTI-CONCUSSION WATER-COCKS.

Specification forming part of Letters Patent No. 123,606, dated February 13, 1872.

Specification describing certain Improvements in Anti-Concussion Water-Cocks, invented by MIFFLIN W. BAILY, of Pottstown, in the county of Montgomery and State of Pennsylvania.

The figure is a detailed sectional view of my improved water-cock.

My invention has for its object to furnish an improved cock for attachment to a water-pipe, which shall be so constructed as to prevent the concussion when the cock is closed and the movement of the column of water checked; and it consists in the combination of an air-chamber with the cock, as hereinafter more fully described.

A is the inlet of the cock, which is designed to be connected with the water-pipe. B is the outlet through which the water is discharged. C is an air-pipe or chamber formed upon the cock. The upper end of the pipe or chamber C is closed, and its lower end communicates with the interior of the cock. D is the plug, which is fitted into the interior of the cock in the ordinary manner. In the lower part of the plug D is formed a perforation, d^1 , so that when the said plug is turned into the position shown in the figure a passage may be opened from the inlet A to the outlet B. In the upper part of the plug D is formed a perforation, d^2 , at such an angle with the perforation d^1 that

when the plug D is turned into such a position as to close the passage between the inlet A and outlet B the perforation d^2 may form a passage from the inlet A through the offset a' formed upon said inlet to the air-chamber C. With this construction, when the plug D is turned to shut off the water a passage is opened into the air-chamber C, so that the movement of the column of water may be checked by the air within said air-chamber and the cock thus relieved from the concussion. When the plug D is turned into such a position as to close the passage leading to the air-chamber C the water in said chamber is forced out through a waste-hole, c' , by the compressed air, and more air passes in to again form a cushion for the water, when the cock is again closed.

Having thus described my invention, what I claim as new, and desire to secure by Letters Patent, is—

The device A B C c^1 a' , combined with cock D, having apertures d^1 d^2 at right angles to each other, when all are constructed and adapted to be used together, as and for the purpose described.

MIFFLIN W. BAILY.
